UNITED STATES PATENT OFFICE.

THOMAS C. JOHNSON, OF NEW HAVEN, CONNECTICUT, ASSIGNOR TO WINCHESTER,
REPEATING ARMS CO., OF NEW HAVEN, CONNECTICUT, A CORPORATION.

LOCKING MECHANISM FOR FIREARMS.

1,299,189.

Specification of Letters Patent. Patented Apr. 1, 1919.

Application filed January 10, 1919. Serial No. 270,496.

To all whom it may concern:

Be it known that I, THOMAS C. JOHNSON, a citizen of the United States, residing at New Haven, in the county of New Haven 5 and State of Connecticut, have invented a new and useful Improvement in Locking Mechanism for Firearms; and I do hereby declare the following, when taken in connection with the accompanying drawings and 10 the characters of reference marked thereon, to be a full, clear, and exact description of the same, and which said drawings constitute part of this application, and represent, in—

Figure 1 a detail broken view, partly in side elevation and partly in central longitudinal section, of a firearm constructed in accordance with my invention.

Fig. 2 a detached plan view of the locking-bolt with the hub of the locking bolt-lever in transverse section in the locked position of the locking-bolt.

Fig. 3 a corresponding view showing the unlocked position of the locking-bolt.

Fig. 4 a detached plan view of the locking-bolt with the hub of the locking bolt-lever in transverse section on the line 4—4 of Fig. 8, showing the stop-cam in its operated position.

Fig. 5 a detached side view of the locking bolt.

Fig. 6 a detached sectional view of the locking bolt-lever in vertical longitudinal section.

Fig. 7 a reverse plan view thereof.

Fig. 8 a front view thereof.

My invention relates to an improvement in locking-mechanism for firearms, the object being to simplify and cheapen the construction thereof.

With these ends in view, my invention consists in a locking-mechanism for firearms, having certain details of construction as will be hereinafter described and pointed out in the claims.

In carrying out my invention as herein shown, it is applied to a single-shot breech-loading firearm in which a barrel 2 hung upon a pivot 3 is provided at its rear end 50 with a beveled locking-lug 4 engaged by the beveled forward end of a locking bolt 5 having an upwardly curved and rearwardly extending arm 6 formed with a longitudinal slot 7 the inner faces of the walls of which 55 are cut away at opposite points to form

curved assembling-grooves 8. The upper face of the arm 6 is formed near its rear end with a shallow transverse groove 9 the rear wall of which forms a transverse operating-shoulder 10. The said locking-bolt 5 is operated by a one-piece locking bolt-lever comprising a finger-piece 11, an integral bearing-hub 12 depending from the forward end thereof, a combined guide and stop-cam 13, and a disk-like supporting and retaining collar 14. A deep transverse cut 15 located between the hub 12 and the combined guide and stop-cam 13 results in the production of a transverse shoulder 16. the left hand corner 16^a of which co-acts with the shoulder 10 at the rear end of the groove 9 in the arm 6, for the retraction of the locking-bolt 5. The combined guide and stop-cam 13 is inclined with reference to the longitudinal axis of the lever, as shown in Fig. 7, and 75 away from the said left hand corner 16^a of the shoulder 16. The member 13 is adapted in size to fit within the slot 7 of the arm 6 which it assists in guiding as the same moves back and forth. It will be understood that 80 all of the above described features of the locking bolt-lever are made in one piece.

The hub 12 of the locking bolt-lever has bearing in a hole 17 formed for its reception in the receiver 18 of the arm. The 85 rounded rear end of the arm 6 of the locking bolt is formed with a conical recess 19 for the reception of the conical nose 20 of a pin 21 encircled by a helical spring 22, and having its rear end entered into a hole 23 in the 90 rear end of the receiver 18. The constant effort of the spring 22 is to force the locking bolt forward into its locked position.

In assembling my improved locking-mechanism, the locking-bolt is slid rearward until 95 its assembling grooves 8 are brought into registration with the bearing-hole 17, whereby the collar 14 of the lever is allowed to pass downward through the slot 7 of the arm 6. The locking bolt is now slid forward until 100 the shoulder 16 of the lever bears against the shoulder 10 of the arm 6. The edges of the collar 14 will now support the rear end of the locking bolt which also retains the locking bolt-lever in place, this being the locked 105 position of the locking-bolt at which time the finger-piece 11 is in line with the longitudinal axis of the arm. The locking-bolt is normally maintained in its locked position 110 by the forward pressure of the spring 22.

To unlock the locking-bolt for opening or "breaking down" the gun, the finger-piece is moved from left to right, whereby the locking-bolt is retracted against the tension of the spring 22 by the pressure of the left hand end 16^a of the shoulder 16 of the locking-bolt-lever against the left hand end of the shoulder 10 of the arm 6 of the locking-bolt, the movement of the locking-bolt-lever from left to right being limited by the engagement of the forwardly projecting end of the combined guide and stop-cam 13 with the left hand wall of the slot 7. As soon as pressure is removed from the finger-piece of the lever, the spring 22 will assert itself to move the locking-bolt again forward into its locking position. Then when the barrel is swung into its closed position, its beveled locking lug 4 will snap over the beveled forward end of the locking-bolt 5 which is at this time momentarily pushed rearward. The swinging of the finger-piece from right to left and therefore out of line with the axis of the gun, is prevented by the engage-

ment of the part 13 of the locking bolt-lever 25 with the right hand wall of the slot 7 of the locking-bolt arm 6.

I claim:

In a locking mechanism for firearms, the combination with a locking bolt provided with a rearwardly extending arm, of a spring exerting a constant effort through the said arm to move the locking-bolt forward, and a one-piece locking bolt-lever comprising a finger-piece, a bearing-hub, a combined 30 guide and cam-stop, a supporting and retaining collar, and an operating shoulder adapted to co-act with the locking-bolt and produced by a transverse cut formed between the said hub and the combined guide 35 and cam-stop.

In testimony whereof I have signed this specification in the presence of two subscribing witnesses.

THOMAS C. JOHNSON
